United States Patent Office.

F. BLECKLE. OF PHILADELPHIA, PENNSYLVANIA.

Design No. 2,690, dated July 2, 1867.

DESIGN FOR KNITTED FABRIC.

The Schedule referred to in these Letters Patent and making part of the same.

TO ALL WHOM IT MAY CONCERN:

Be it known that I, F. BLECKLE, of Philadelphia, county of Philadelphia, State of Pennsylvania, have invented or produced a new and original Design for a Knitted Fabric; and I do hereby declare that the accompanying drawing, and the following explanation thereof, form a full, clear, and exact description of the said design.

In the accompanying drawing, the figure represents a section of a knitted fabric, on the surface of which are rows of circular, or nearly circular, projections, *a*, the projections in one row being opposite the spaces between the projections in the adjacent row.

I claim the design for a knitted fabric, substantially as shown in and by the accompanying drawing.
In testimony whereof I have signed my name to this specification in the presence of two subscribing witnesses.

Witnesses:

CHARLES E. FOSTER,
W. J. R. DELANY.
